MULTI-COIN BANKING MACHINE

George A. Pebbles, Miami, Fla.
(5532 Eskridge #5, Houston, Tex. 77023)

Filed May 3, 1967, Ser. No. 6,940

Term of patent 14 years

(Cl. D34—11)

FIG. 1

FIG. 2

FIG. 3

FIG. 1 is a front elevation of a multi-coin banking machine showing my new design.

FIG. 2 is a side elevation thereof.

FIG. 3 is a perspective view thereof.

The rear and bottom sides are plain.

The side not shown is the same as that shown in FIG. 2.

The broken lines shown in the figures are for illustrative purposes only.

I claim:

The ornamental design for a multi-coin banking machine, as shown and described.
